30 Claims. (Cl. 230—56)

My invention relates to motor compressors of the type in which the compressing pistons are driven directly by the energy derived from the combustion of a fuel.

5 Simple compressors of that type comprise at least one pair of opposed pistons adapted to reciprocate freely in a common cylinder. The mixture of air and fuel is fed into said cylinder between said pistons, where it explodes, 10 while the outer faces of the two pistons reciprocate in two separate cylinders respectively and serve to compress the air therein. The chief problem in connection with compressors of that type is to insure a satisfactory return or in- 15 ward stroke of the pistons in spite of possible variations in the length of the outward stroke.

The object of the present invention is to provide a motor compressor of that type in which variations in the length of the outward stroke 20 are not detrimental to a satisfactory running of the compressor.

The motor compressor according to my invention comprises at least two simple compressors of the type above referred to, the two pairs of 25 pistons of which are respectively coupled together through positive means so that the outward stroke of one pair of pistons is made to control the inward stroke of the other pair. In that way the energy for the return stroke of 30 one pair of pistons is equal to the sum of the energy stored in the air compressed in the dead spaces of the compressing cylinders of said pair of pistons and of the energy supplied by the explosive mixture between the pistons of the 35 other pair. Such a motor compressor is adapted to work within a certain range of values of said energy.

According to my invention, the simple compressors are so devised as to meet the two following conditions:

(a) When the energy for the return stroke of one pair of pistons, that is to say when the sum of the energy stored in the air compressed in the compressing cylinders of said pair of pistons, and of the energy of the explosive mixture present between the pistons of the other pair falls to its lowest admissible value, an accidental decrease in the length of stroke of the pistons causes the energy of the explosive mixture to decrease by an amount at most equal to that by which the energy stored in the compression cylinders increases.

(b) When the energy for the return stroke reaches its highest admissible value, an accidental increase in the length of stroke of the pistons causes said energy of the explosive mixture to increase by an amount at most equal to that by which the energy stored in the compression cylinders decreases.

tons causes said energy of the explosive mixture to increase by an amount at most equal to that by which decreases the energy stored in the compression cylinders of the other pair of pistons.

Other characteristics of my invention will appear from the following description.

Preferred embodiments of my invention will be hereinafter described with reference to the accompanying drawings, given merely by way of example, and in which:

Fig. 1 is a diagrammatical view showing in longitudinal section a motor compressor having two pairs of pistons according to my invention;

Fig. 2 is a diagram of the compression exerted by the outer faces of the pistons;

Fig. 3 is a diagram of the variations of pressure in the combustion chamber between two pistons;

Fig. 4 is a diagrammatical view showing in longitudinal section another embodiment of a motor compressor having two pairs of pistons according to my invention;

Fig. 5 is a similar view of still another embodiment;

Fig. 6 is a longitudinal section of a motor compressor having three pairs of pistons according to my invention;

Fig. 7 is a side view of the device of Fig. 6, partly cut away;

Fig. 8 is a diagrammatical view of a motor compressor unit provided with an automatic adjusting device;

Fig. 9 is a diagrammatical view of a similar motor compressor unit provided with another automatic adjusting device;

Fig. 10 is a diagrammatical view of a motor compressor unit provided with still another automatic adjusting device;

Fig. 11 is a diagrammatical view of a motor unit consisting of two simple motor compressors and provided with a safety stop device.

The motor compressor of Fig. 1 comprises four pistons, 1, 2, 3, and 4. Pistons 1 and 2 reciprocate on the one hand both in cylinder 5 which is the power cylinder, and on the other hand in cylinders 6 and 7 respectively, which are the air compression cylinders. In a like-wise manner, pistons 3 and 4 reciprocate on the one hand both in cylinder 8 and on the other hand each in cylinders 9 and 10 respectively. Pistons 2 and 3 are connected together by a rack 11. Rack 11 meshes with two pinions 12 which, on the other hand, mesh with two racks 14 respectively. Toothed pinions 12 are carried by an

50

55

equalizing bar 13 pivoted about axis 45. Racks 14 are carried by rods 15 and 16 which connect pistons 1 and 4, together.

The cycle in cylinders 5 and 8 takes place in the known manner for two stroke engines with opposed pistons in which the scavenging is effected through suitably disposed ports. Pistons 1 and 2, which in the drawings are shown at or near the inner ends of their stroke, are driven apart by the combustion of the fuel in cylinder 5. They impart their movement, through rods 15 and 16 and rack 11, to pistons 4 and 3 respectively and bring said pistons back toward each other until, due to ignition of the fuel in cylinder 8, the outward stroke of said pistons 3 and 4 takes place, which then drives pistons 1 and 2 back toward each other. During the outward stroke of pistons 1 and 2, air is compressed in cylinders 6 and 7, from which it passes, through suitable valves into a compressed air storage tank. The compressed air cushions remaining in the dead spaces of said compression cylinders 6 and 7 also help in driving pistons 1 and 2 during the inward stroke thereof. In a likewise manner, the air remaining in the dead spaces of compression cylinders 9 and 10 also helps in bringing pistons 3 and 4 back to their inner positions.

Pinions 12, which mesh with rack 11 on the one hand and racks 14 respectively on the other hand, serve to synchronize the movements of the two pairs of pistons. As a matter of fact, it may happen that, due to differences in the resistances that they meet with, the two pairs of pistons tend to move with different speeds. Owing to the presence of said pinions carried by an equalizing lever 13 pivoted at 45, that tendency is corrected.

It results from the above described operation that the energy for the return stroke of, say, pistons 1 and 2 results from both the compression of air in the dead spaces of cylinders 6 and 7 and the combustion of the explosive mixture in cylinder 8. It will now be shown how, according to applicant's arrangement, said energy for the return stroke of pistons 1 and 2 meets the conditions above stated. This will be better understood by referring to the diagrams of Figs. 2 and 3. It will be supposed that Fig. 2 shows the variations of pressure in chambers 6 and 1. The pressures are plotted in ordinates and the lengths of stroke in abscissas. As for Fig. 3 it shows the variations of pressure in chamber 8. The pressures are plotted in ordinates and the lengths of stroke in abscissas. As pistons 2 and 3 and pistons 1 and 4 are rigidly connected together, their linear displacements are exactly equal. Consequently, the graphs of Figs. 2 and 3 have been placed exactly over each other so that their abscissas may correspond.

If it be supposed that the length of the outward stroke of pistons 1 and 2 is ai (Fig. 2) and therefore that the length of the inward stroke of pistons 3 and 4 is nv (Fig. 3), equal to ab , then the diagram of pressures in chamber 1 will be $abcd$ (Fig. 2), while the diagram of pressures in chamber 8 will be $nopm$ (Fig. 3). It follows that the energy for the return of pistons 1 and 2 will be proportional to the sum of the areas icd (Fig. 2) and $nvpm$ (Fig. 3). Of course, the ordinates have been plotted on different scales in the graphs of Figs. 2 and 3 so as to take into account, and compensate for, the differences in the areas of the piston faces on

which the gases compressed in cylinders 6 and 1 on the one hand, and those in chamber 8 on the other hand, can act respectively.

As in all two stroke engines of this type, the cycle in motor cylinder 5 is such as to allow for a certain range of variations of that energy for the return of pistons 1 and 2, the lowest admissible value of that energy being that which corresponds to a heating of the combustion air sufficient for igniting the fuel at the end of the compression stroke, and the highest admissible value of that energy being that above which the apparatus might risk to be injured.

These limits being fixed, according to my invention, I choose the dimensions of the compressor elements (bores of the cylinders, dead spaces of the air compression cylinders) in such manner that, when the energy for the return of one pair of pistons falls to its lowest admissible value, an accidental decrease of the stroke of the pistons is not capable of further reducing said energy, and when the energy for the return of one pair of pistons reaches its highest admissible value, an accidental decrease of the stroke of the pistons is not capable of further increasing said energy.

Thus, if, in the diagrams of Figs. 2 and 3, the length of stroke ai (Fig. 2) and nv (Fig. 3) is supposed to correspond to the lowest admissible energy for the return of pistons 1 and 2, if there occurs an accidental reduction of said length of stroke so that it becomes ak (Fig. 2) (nu in Fig. 3), the new diagrams of pressures will be $abef$ (Fig. 2) in cylinders 6 and 1 and $nrqm$ (Fig. 3) in cylinder 8. The energy for the return of pistons 1 and 2 will therefore be proportional to the sum of the areas kef (Fig. 2) and $nuqm$ (Fig. 3).

According to my invention, the dimensions of the various elements of the compressor are so chosen that that sum is at least equal to the sum of areas icd and $nvpm$ corresponding to the case of a stroke of the pistons equal to ai (and nv). This is due to the fact that, if area $nuqm$ is smaller than area $nvpm$, on the contrary area kef is larger than area icd , and the difference between areas $nvpm$ and $nuqm$ is at most equal to the difference between areas kef and icd .

On the contrary, if, in the diagrams of Fig. 2 and 3, the length of stroke ai (Fig. 2) and nv (Fig. 3) is supposed to correspond to the highest admissible energy for the return of pistons 1 and 2, if there occurs an accidental increase of said length of stroke so that it becomes ae (Fig. 2) (nw in Fig. 3), the energy stored in cylinder 8 is increased (since it corresponds to area $nwSm$ instead of area $nvpm$) but the energy stored in the dead spaces of cylinders 6 and 7 is diminished (since it corresponds to area egh instead of area icd). The energy for the return of pistons 1 and 2 will therefore be proportional to the sum of areas $nwSm$ (Fig. 3) and egh (Fig. 2).

According to my invention, the dimensions of the various elements of the compressor are so chosen that said sum is at most equal to the sum of areas icd and $nvpm$ corresponding to the case of a stroke of the pistons equal to ai (and nv). This is due to the fact that, if area $nwSm$ is larger than area $nvpm$, on the contrary area egh is smaller than area icd , and the difference between areas $nwSm$ and $nvpm$, is at most equal to the difference between areas icd and egh .

The device according to my invention further permits the regulation of the engine 75

through variation of the injection of fuel. It is possible to run under half load by causing one of the simple compressors to run idle by opening the valves of the compressing cylinders 8 and 10 for instance and injecting no fuel into cylinder 8. That cylinder then operates as a compensating air chamber in a known manner.

The valves are not shown in Fig. 1. They may be disposed in the known manner in the 10 cylinder head or ends.

In the embodiment of Fig. 4, the two pairs of pistons 21, 22 and 23, 24 are adapted to reciprocate in two cylinders disposed side by side. The combustion chambers of said cylinders are 25, 15 26 respectively, while the compression chambers are 27, 28 and 29, 30 respectively. Pistons 21 and 24 are connected together through a rod 31, and pistons 22 and 23 are connected together through a rod 32. Pistons 22 and 24 are provided respectively with rods 33 and 34 which project outwardly from the cylinders and are connected through cranks 35 and 36 with an equalizing bar 38 pivoted about axis 37.

The operation of such a device is obviously 25 similar to that described with reference to Fig. 1. Rods 31 and 32 play the parts of rack 11 on the one hand and rods 15 and 16 on the other hand. The movements of the two pairs of pistons are synchronized by equalizing bar 37.

In the embodiment of Fig. 5 the pistons and cylinders are disposed as in the embodiment of Fig. 4. The connection between the two pairs of pistons is furnished by piston rods 39, 40, 41, 42 which project from both ends of the cylinders 35 and are connected through cranks 43 with equalizing bars 46, 47 pivoted about axes 45, 44 respectively. Said equalizing bars are provided with toothed sectors 48 and 49 which mesh with bevel pinions 50, 51 respectively. Said pinions are 40 connected through a shaft 52 on which they are keyed. In this case also the operation of the device is similar to that of the device of Fig. 1. Levers 46 and 47, together with the piston rods connected thereto, play the parts of rack 11 and rods 15 and 16 of the embodiment of Fig. 1. Toothed sectors 48, 49 with their co-operating pinions 50, 51 play the part of pinions 12 of the embodiment of Fig. 1.

I may also, as shown in Fig. 6, apply the principle of my invention to the case of a compressor having more than two pairs of pistons. In the embodiment of Fig. 6, the compressor comprises three pairs of pistons, 53—56, 54—57 and 55—58. Pistons 53 and 55 are connected with each other 55 and with piston 57 through bent rods 59 provided with racks 61. Pistons 56 and 58 are connected with each other and with piston 54 through bent rods 60 provided with racks 62. Racks 61 and 62 mesh with pinions 63 carried by the compressor casing or frame. In this case the outer stroke of the two outer pairs of pistons corresponds to the inward stroke of only one pair of pistons, namely 54—57. On the contrary, the outward stroke of the last mentioned pair of 65 pistons corresponds to the inward stroke of the two other pairs of pistons. The advantage of that embodiment lies in the symmetry of the elements for connecting together the several pairs of pistons.

Of course, in the embodiments of Figs. 4, 5 and 6, the conditions concerning the dimensions of the elements of the compressor are the same as above explained concerning the embodiment of Fig. 1, so that accidental variations in the 75 lengths of stroke of the pistons may be corrected

as above explained with reference to Figs. 2 and 3.

Another very important problem relating to motor compressors of the type above referred to, is to regulate the amount of fuel fed to the power cylinders according to the circumstances under which the machine is working, and in particular when the compressor is being started. Otherwise, due to the rapid increase of the energy resulting from the rate of compression of 10 the air in the power cylinders, the machine might be very quickly injured, for instance by the power cylinders bursting.

The regulating means that are already known and applied to simple motor compressors of the 15 type with which my invention is concerned, are adapted to proportionate the amount of fuel fed to the power cylinders to the output of compressed gas that is produced. Said means are hardly applicable to multiple motor compressors, 20 for instance to motor compressors consisting of two simple motor compressors coupled together since the variations of output of the compressors are very small because the variation of the length of stroke of the pistons are themselves 25 necessarily very limited.

One object of my invention is to provide a system of regulating multiple motor compressors of the type above referred to.

According to a first embodiment the feed of 30 the various injection pumps is adjusted according to the exhaust pressure (which is very low when the machine is being started) so that said feed diminishes when that pressure decreases. Furthermore, I preferably dispose on the outlet 33 pipe of the multiple motor compressors, a throttling valve 0 which is sensitive to variations of the pressure existing in front of said organ, so that when said pressure rises above a determined maximum, the valve is closed thus 40 shutting off said pipe and directing the discharged gases toward the atmosphere, or toward a chamber in which the pressure is relatively low.

Such an arrangement is shown in Fig. 8 which 45 shows a motor compressor consisting of two simple or elementary compressors A and B, coupled together as above described. These simple or elementary compressors are fed through injection pumps 133 and 134, comprising 50 regulating rods 135, 136 respectively.

Said rods are connected, through suitable mechanical means, to an organ sensitive to the pressure existing in outlet main 137, so that when said pressure is low the amount of fuel 55 that is fed may be small, and on the contrary when that said pressure is high, the amount of fuel fed to the power cylinders is relatively great.

The element above referred to may comprise 60 for instance, a cylinder 138 in which moves a piston 139 one of the faces of which is subjected to the exhaust pressure, so that said pressure tends to move said piston against the action of 65 a return spring.

I dispose between the outlet main 137 and the reservoir 140 to be fed with compressed gas, a throttle valve 0 adapted to operate as above explained. That throttle valve may consist for 70 instance of a cylinder 141, in which move two pistons 142 and 143 connected to each other through a rod 144, and pushed by suitable elastic means against a stop 141. The face of piston 142 that is located on the side of said stop is 75

connected with reservoir 140. Three ports 145, 146 and 147 are provided in the wall of cylinder 141, so that port 145 communicates with reservoir 140, port 146 communicates with main 137 and port 147 communicates with the atmosphere. The whole is so arranged that port 146 is always located between pistons 142 and 143 whatever their position may be. On the other hand when the pistons are in contact with stop 141¹, port 145 is located between the pistons and port 147 is covered by piston 143. Finally when the pistons have moved against the action of the elastic means, port 145 is covered by piston 142 and port 147 is located between the pistons.

15 The elastic means above referred to advantageously comprise on the one hand a spring 148 that constantly pushes the piston toward stop 141¹, and on the other hand at least two springs 149, 150 pivoted to fixed points so that 20 said springs acting alternately in the direction of spring 148, and in the opposite direction, make it possible to automatically obtain a more rapid working of the valve.

This multiple motor compressor operates as 25 follows:

If the pressure in reservoir 140 rises above a certain value, throttle valve 0 connects the outlet pipe 131 of the compressor with the atmosphere, and the piston 139 of the fuel regulating system displaces regulating rods 135 and 136 so that these rods diminish the quantity of fuel fed into the power cylinders.

On the contrary, if the pressure in reservoir 140 falls below a certain value, the valve establishes a connection between outlet pipe 131 and said reservoir 140 and according to the value of the exhaust pressure which may be equal to zero, especially when the machine is being started, piston 139, subjected to a force proportional to said pressure, acts in a suitable manner 40 on the control rods of the feed pumps.

According to another embodiment of my invention, the feed regulating means and the outlet slide valve as described with reference to the preceding embodiment, are connected with only 45 some of the simple or elementary motor compressors. The means for feeding fuel into the other simple or elementary motor compressors depend directly on the pressure existing in reservoir 140 fed by the machine.

Owing to this arrangement, it will be understood that when the first mentioned elementary compressors are caused to run idle by the action of throttle valve 0 the other elementary 55 compressors may work as ordinary simple motor compressors, the compensating cushions of which will be furnished by the power cylinders of the first mentioned elementary compressors.

The latter may then work under any working 60 conditions between the running under no-load and the running under their full load, which corresponds to the half load of the complete machine if said machine comprises an even number of elementary compressors.

65 Such an arrangement is disclosed in Fig. 9 which shows a motor compressor consisting of two elementary compressors A and B.

A throttle valve 0 similar to that above described, is inserted between the exhaust main 70 151 of the elementary compressor B, and reservoir 140. The feed of fuel to said elementary compressor B is regulated through a device similar to that described with reference to Fig. 8, comprising for instance a cylinder 138 and a 75 piston 139.

The exhaust main 152 of elementary compressor A is directly connected to reservoir 140. The feed of fuel to said elementary compressor A is regulated through a device (comprising for instance a cylinder 153 and a piston 153^a) sensitive 5 to the variations of the pressure existing in reservoir 140.

Advantageously throttle valve 0 is adjusted in such manner that it connects main 151 with the atmosphere for all the pressures that are higher 10 than a certain limit. Above said limit, the amount of fuel fed by pump 134, which is regulated by the action of the organ 138, 139 sensitive to the variations of the pressure in main 151, is equal to zero or extremely small. The power 15 cylinder of elementary compressor B then acts as a compensating cushion adapted to cooperate with elementary motor compressor A. As for the air compression cylinders of elementary compressor B, they take up and give back an insignificant energy, because they are in communication with the atmosphere.

The element 153, 153^a for regulating the feed of fuel to elementary compressor A, the exhaust main 152 of which is constantly in communication with reservoir 140, is so adjusted that on the one hand below the limit pressure above which the throttle valve 0 causes elementary compressor B to run idle, the amount of fuel fed by pump 133 increases with the pressure existing 30 in said reservoir, and this preferably according to the same law as for pump 134, but on the other hand, above said limit pressure, the amount of fuel fed by pump 133 decreases when the pressure further increases in reservoir 140, 35 that is to say when the need of compressed air diminishes until the maximum pressure is reached in said reservoir and elementary compressor A itself runs idle.

Although the regulating element acts always in 40 the same direction on the rod 135 of pump 133, a special arrangement of said pump will make it possible to obtain the desired result, to wit, that from a certain pressure up the amount of fuel fed by pump 133 must decrease, although, as a 45 result of the still increasing pressure, rod 135 is still moving in the same direction.

To this effect according to my invention, I cause rod 135 to control by a cam of such an outline that from said limit pressure up the variation 50 of feed of pump 133 may be reversed.

A third embodiment of the regulating device for multiple motor compressors according to my invention is more particularly adapted to be applied to machines of that kind for operating a 55 receiving device without the addition of an intermediate reservoir. The chief feature of this embodiment is to provide the receiving device with a governor R which is connected with a distributing valve for controlling the inflow of 60 the motive fluid to the receiving device, so that the pressure of said fluid and therefore the discharge pressure of the motor compressor vary in accordance with the speed of the receiving device, so as to decrease when said speed itself 65 decreases. Furthermore, means are provided for varying the amount of fuel fed to the motor compressor in accordance with said exhaust pressure, so that the feed decreases when said pressure itself decreases.

Such an arrangement is disclosed in Fig. 10, 70 which shows a turbine having four stages, 154, 155, 156 and 157. A distributing element is so arranged that according to the position of a slide valve 158, exhaust main 159 of the motor com- 75

pressor is connected with one or the other of the four stages of the turbine. To this effect slide valve 158 may consist of a sliding member provided with four ports 160, 161, 162 and 163 adapted to coact with conduits 164, 165, 166 and 167 respectively connected to the four stages of the turbine so that when the slide valve is moved from one of its extreme positions to the other one, it successively directs the motive fluid into conduits 164, 165, 166 and 167.

Slide valve 158 is so connected to centrifugal governor R that at low speeds of revolution, the fluid is fed into the high pressure stage, and then, as the speed of revolution increases successively toward stages of decreasing pressure.

Advantageously, instead of positively connecting said sliding valve with centrifugal governor R, these elements are elastically connected together, for instance through a spring 168, and slide valve 158 is so arranged (for instance by providing it with a piston 169 subjected to the exhaust pressure) that said spring may be the more compressed as said pressure is higher. Thus the passage from one stage to the next stage of lower pressure is delayed if the exhaust pressure is higher than the mean pressure, and is advanced if that pressure is smaller than it.

Finally, I provide means as above described for regulating the fuel feed, which may consist for instance of cylinder 170 and a piston 171, sensitive to variations of the pressure existing in main 159.

Owing to this arrangement if the load under which the turbine is running tends for instance to decrease, the rotor tends to revolve faster; governor R acts on slide valve 158 so that the compressed fluid instead of entering the receiver through the high pressure stage 154, enters through a stage of lower pressure. This produces an immediate decrease of pressure in the exhaust main, and therefore under the action of regulating organ 170, 171, decreases the amount of fuel fed to the power cylinders.

Of course a reverse action (increase of the load under which the turbine runs) would bring a reverse variation of the feed of the pumps.

It should be noted that the receiver may be of any kind whatever, either staged or not, either rotary or not. In particular it might quite well consist of a piston machine, for instance of the compound type.

Whatever be the embodiment that is chosen, I advantageously fit the motor compressor of the type above described with a safety device adapted to stop the engine when the length of stroke of the pistons reaches the maximum admissible for the machine. Such an arrangement is shown in Fig. 11 in which the two pistons 1 and 2 of a given elementary compressor are connected through rods 72, 73 jointed to the ends of an oscillating lever 74 controlling feed pumps 133, 134 through elements such as cams 75 of suitable outline.

The angles of oscillation are so chosen that when said rods move beyond their cinematic dead centre, which corresponds to a value of the length of stroke equal to the upper limit thereof, they bring the oscillating lever into a new angular zone in which at least one of the cams ceases to act on the corresponding elements for controlling the feed pumps so that the machine is then immediately stopped.

While I have described what I deem to be practical and efficient embodiments of my invention, it should be well understood that I do

not wish to be limited thereto as there might be changes made in the arrangement, disposition and form of the parts without departing from the principle of my invention as comprehended within the scope of the appended claims.

What I claim is:

1. A motor compressor of the type described comprising in combination, at least two power cylinders, at least two pairs of opposed pistons adapted to reciprocate in said cylinders respectively, means for feeding fuel into said cylinders, at least two pairs of compression cylinders adapted to receive the outer ends of said two pairs of pistons respectively, connecting means between the pistons of said two pairs respectively for causing the outward stroke of one pair to imperatively control the inward stroke of the other pair, the dimensions of said parts being so chosen that, when the sum of the energy of the explosive mixture in one power cylinder and of the energy stored in the fluid compressed at the end of the compression stroke in the compression cylinders corresponding to the other cylinder falls down to its lowest admissible value, an accidental decrease in the length of stroke of the pistons causes said energy of the explosive mixture to decrease by an amount at most equal to that by which the energy stored in said compression cylinders decreases, and when said sum reaches its highest admissible value an accidental increase in the length of stroke of the pistons causes said energy of the explosive mixture to increase by an amount at most equal to that by which the energy stored in said compression cylinders decreases.

2. A motor compressor of the type described comprising in combination, two power cylinders in line with each other, two pairs of opposed pistons adapted to reciprocate in said cylinders respectively, two pairs of compression cylinders disposed on opposite sides of the first mentioned cylinders respectively and adapted to receive the outer ends of the pistons of said first mentioned cylinders respectively, and means for rigidly connecting one piston of one pair to the opposite piston of the other pair.

3. A motor compressor of the type described comprising in combination, two power cylinders in line with each other, two pairs of opposed pistons adapted to reciprocate in said cylinders respectively, two pairs of compression cylinders disposed on opposite sides of the first mentioned cylinders respectively and adapted to receive the outer ends of the pistons of said first mentioned cylinders respectively, a rod for rigidly connecting together the two adjacent pistons of the two pairs respectively, two rods, one on each side of the first mentioned rod, for rigidly connecting together the two other pistons of said pairs respectively, two racks, one on each side of the first mentioned rod, facing the two second mentioned rods respectively, a rack on one side of each of the two second mentioned rods facing one of the two above mentioned racks respectively, an equalizing lever pivoted about a central axis at right angles to the plane of said three rods, two pinions pivoted on said lever on either side of said axis and adapted to mesh each on the one hand with one rack of the first mentioned rod and on the other hand with the rack of one of the two other rods.

4. A motor compressor of the type described, comprising in combination, two power cylinders disposed side by side, two pairs of opposed pistons adapted to reciprocate in said cylinders re-

spectively, two pairs of compression cylinders disposed on opposite sides of the first mentioned cylinders respectively and adapted to receive the outer ends of the pistons of said first mentioned 5 cylinders respectively, two rods each articulated at one end to one of the pistons of one pair and at the other end to the opposite piston of the other pair, two rods rigidly fixed to adjacent pistons of the two pairs respectively projecting outwardly from the outer ends of the corresponding compression cylinders, and an equalizing bar pivoted about a fixed axis and articulated at both ends with the two last mentioned rods respectively.

15 5. A motor compressor of the type described, comprising in combination, two power cylinders disposed side by side, two pairs of opposed pistons adapted to reciprocate in said cylinders respectively, two pairs of compression cylinders 20 disposed on opposite sides of the first mentioned cylinders respectively and adapted to receive the outer ends of the pistons of said first mentioned cylinders respectively, two rods, substantially coaxial with said cylinders respectively, rigidly 25 fixed to the adjacent pistons of the two pairs respectively and projecting outwardly from the outer ends of the corresponding compression cylinders, two other rods, substantially coaxial with said cylinders respectively, rigidly fixed to the 30 other adjacent pistons of the two pairs respectively and projecting outwardly from the outer ends of the corresponding compression cylinders, two levers pivoted about axes at right angles to the common plane of the two cylinders, each lever 35 being articulated at both ends with the outer ends of said two pairs of rods respectively, a toothed sector carried by each of said levers, a shaft extending longitudinally between the two cylinders, and toothed means keyed at each end of said 40 shaft for engaging said toothed sectors respectively.

6. A motor compressor of the type described comprising in combination, at least three parallel cylinders disposed side by side, a pair of pistons 45 adapted to reciprocate in each of said cylinders, three pairs of compression cylinders disposed on opposite sides of the three first mentioned cylinders respectively, rigid means for connecting together one piston of the central 50 cylinder with both of the two opposite pistons of the outer cylinders, rigid means for connecting together the other piston of the central cylinder with both of the two opposite pistons of the outer cylinders, and equalizing means between 55 the two last mentioned means for synchronizing the movements of the two groups of three pistons.

7. A motor compressor of the type described, comprising in combination, three parallel cylinders disposed side by side, a pair of pistons 60 adapted to reciprocate in each of said cylinders, three pairs of compression cylinders disposed on opposite sides of the three first mentioned cylinders respectively, rigid means for connecting together one piston of the central cylinder with both of the two opposite pistons of the outer cylinders respectively, rigid means for connecting together the other piston of the central cylinder with both of the two opposite pistons of the outer cylinders respectively, a rack carried by 65 the first mentioned rigid means, another rack, facing the first mentioned one, carried by the second mentioned rigid means, and a pinion, journalled about a fixed axis with respect to the 70 cylinders, in mesh with both of said racks.

8. A compressor according to claim 7 in which the axes of the three first mentioned cylinders are in the same plane, the two racks and cooperating pinion being all disposed on one side of said plane, the compressor further comprising 5 a similar system of two racks and a cooperating pinion symmetrically disposed on the other side of said plane.

9. A motor compressor of the type described comprising in combination, at least two power 10 cylinders, at least two pairs of opposed pistons adapted to reciprocate in said cylinders respectively, feeding means for injecting fuel into said cylinders respectively, at least two pairs of compression cylinders adapted to receive the outer 15 ends of said two pairs of pistons respectively, connecting means between the pistons of said two pairs respectively for causing the outward stroke of one pair to imperatively control the inward stroke of the other pair, a reservoir, an outlet 20 pipe for connecting at least one of said pairs of compression cylinders to said reservoir, means provided on said pipe and sensitive to the pressure in said reservoir for connecting said pipe alternately to said reservoir or to the atmosphere 25 according to the pressure in said reservoir, and means sensitive to the pressure in said pipe for controlling the feeding means of the power cylinders corresponding to the last mentioned compression cylinders. 30

10. A motor compressor according to claim 9 in which the means for connecting said pipe alternately to said reservoir or to the atmosphere comprises, a cylinder provided at one end with a port connected with said reservoir, at the other 35 end with a port connected to the atmosphere, and in its intermediate part with a port connected with said pipe, two pistons rigidly connected together adapted to slide in the last mentioned cylinder, and elastic means for urging 40 said pistons toward the position for which the first mentioned port is covered by one of the pistons.

11. A motor compressor according to claim 9 in which the means for controlling the feeding 45 means comprises, at least one rod for regulating said feeding means, a cylinder connected at one end with said outlet pipe, and a piston in the last mentioned cylinder operatively connected with said rod. 50

12. A motor compressor of the type described comprising in combination, at least two power cylinders, at least two pairs of opposed pistons adapted to reciprocate in said cylinders respectively, feeding means for injecting fuel into 55 said cylinders respectively, at least two pairs of compression cylinders adapted to receive the outer ends of said two pairs of pistons respectively, and connecting means between the pistons of said two pairs respectively for causing 60 the outward stroke of one pair to imperatively control the inward stroke of the other pair, a reservoir, a main outlet pipe for connecting the whole of said pairs of compression cylinders to said reservoir, means provided on said pipe and 65 sensitive to the pressure in said reservoir for connecting said pipe alternately to said reservoir or to the atmosphere according to the pressure in said reservoir, and means sensitive to the pressure in said pipe for controlling said 70 feeding means.

13. A motor compressor of the type described comprising in combination, at least two power cylinders, at least two pairs of opposed pistons adapted to reciprocate in said cylinders, respec- 75

tively, feeding means for injecting fuel into said cylinders respectively, at least two pairs of compression cylinders adapted to receive the outer ends of said two pairs of pistons respectively, 5 connecting means between the pistons of said two pairs respectively for causing the outward stroke of the other pair, a reservoir, at least two outlet pipes for connecting said pairs of compression cylinders to said reservoir respectively, 10 means provided on some of said pipes and sensitive to the pressure in said reservoir for connecting the last mentioned pipes alternately to said reservoir or to the atmosphere according to the pressure in said reservoir, and 15 means sensitive to the pressure in said pipe for controlling the feeding means of the power cylinder corresponding to the last mentioned compression cylinder.

14. A motor compressor according to claim 13, 20 further comprising a means sensitive to the pressure in said reservoir for controlling the feeding means of the other power cylinders.

15. A motor compressor according to claim 13, 25 further comprising a means sensitive to the pressure in said reservoir for progressively reducing the amount of fuel supplied by the feeding means of the other power cylinders when the pressure in said reservoir is above the limit for which the above mentioned pipes are connected to the atmosphere.

16. A motor compressor of the type described comprising in combination, at least two power cylinders, at least two pairs of opposed pistons adapted to reciprocate in said cylinders respectively, 30 feeding means for injecting fuel into said cylinders, at least two pairs of compression cylinders adapted to receive the outer ends of said two pairs of pistons respectively, and connecting means between the pistons of said two pairs respectively for causing the outward stroke of one pair to imperatively control the inward stroke of the other pair, a receiving machine adapted to be operated by the fluid under pressure from said compressor, a speed governor 35 coupled to said machine, an outlet pipe for conveying the fluid under pressure from said compression cylinders to said machine, distributing means in said pipe operatively connected to said governor for controlling the inflow of fluid to the machine so that the pressure of the fluid decreases when the working speed of the machine itself decreases, and means sensitive to said pressure for controlling said feeding means so that the amount of fuel fed to the power 40 cylinders decreases when said pressure itself decreases.

17. A device according to claim 16 in which said machine consists of a turbine having several stages, the distributing means being adapted 45 to direct the fluid to the high pressure stage when the working speed of the turbine is low and successively to lower and lower stages of pressure as said speed increases.

18. A motor-compressor comprising motor and 50 compression cylinders, at least two pairs of pistons adapted to reciprocate in said cylinders, and means connecting said pairs of pistons to force the pistons of one pair to approach each other as those of the other pair move apart, 55 said compression cylinders having dead spaces therein, the size of the motor cylinders and of the dead spaces in the compression cylinders being so chosen that a decrease in the energy developed in the motor cylinder of either pair of pistons is accompanied by an increase in the

energy stored in the dead spaces of the cylinders of the other pair of pistons, while an increase in the energy developed in the motor cylinder of either pair of pistons is accompanied by a decrease in the energy stored in the dead 5 spaces of the cylinders of the other pair, whereby the compression produced is maintained within predetermined limits.

19. A motor compressor of the type described comprising in combination, two cylinders in line 10 with each other, two pairs of opposed pistons adapted to reciprocate in said cylinders respectively, two pairs of compression cylinders disposed on opposite sides of the first mentioned cylinders respectively and adapted to receive the 15 outer ends of the pistons of said first mentioned cylinders respectively, a rod for rigidly connecting together the two adjacent pistons of the two pairs respectively, a rod on one side of the first mentioned rod for rigidly connecting together the two other pistons of said pairs, a rack on one side of the first mentioned rod facing the second mentioned rod, a rack on one side of the second mentioned rod facing the above mentioned rack, an equalizing lever pivoted about a central axis at right angles to the plane of said rods, a pinion pivoted on said lever on one side of said axis and adapted to mesh with said racks.

20. A motor compressor of the type described 30 comprising in combination, a power cylinder and a pair of opposed pistons adapted to reciprocate in said cylinder, means to feed fuel to said cylinder, an equalizing lever for synchronizing the movements of said pistons, and a cam 35 integral with said lever for controlling said feeding means, all the parts being so arranged that when the pistons reach their outermost positions the said lever is brought into an angular position for which said cam is in inoperative position. 40

21. A motor compressor, comprising in combination, a power cylinder and a pair of opposed pistons adapted to reciprocate in said cylinder, means to feed fuel to said cylinder, a 45 single equalizing lever for synchronizing the movements of said pistons, a plurality of cams all carried by said lever for controlling said feeding means, all the parts being so arranged that when the pistons reach their outermost position the said lever is brought into an angular 50 position for which at least one of said cams is in inoperative position.

22. A motor compressor consisting of at least two motor compressor units having motor and 55 compression cylinders and with reciprocating pairs of pistons in said cylinders, said units being arranged side by side with the axes of their cylinders parallel, and rods connecting the pistons of the two units, so arranged that the 60 pistons do not exert any substantial lateral pressure on the cylinder walls.

23. A motor compressor comprising motor and compression cylinders, at least two pairs of pistons adapted to reciprocate in said cylinders, and 65 means connecting said pairs of pistons to force the pistons of one pair to approach each other as those of the other pair move apart, a rack connected to the connecting means of one pair of pistons and a second rack connected to the 70 connecting means of the other pair of pistons, and gear means engaged by both said racks.

24. In a motor compressor consisting of at least two motor compressor units each having motor and compressor pistons and motor and 75

compressor cylinders, means connecting said units in such a manner that the working stroke of the motor part of one of the units both moves its own compressor piston and simultaneously causes the compression stroke of the motor piston and the suction stroke of the compressor of the other unit, means connected to the compression cylinder of at least one of said units to conduct the compressed air away from said last named cylinder, means in said conducting means operated when the pressure therein exceeds a predetermined amount to connect said conducting means to a space in which the pressure is lower than said predetermined amount, means to supply fuel to the motor cylinders, and means controlled by the pressure in said conducting means to reduce the feed of fuel to at least one of said motor cylinders as the pressure in said conducting means decreases.

25. In a motor compressor consisting of at least two motor compressor units each having motor and compressor pistons and motor and compressor cylinders, means connecting said units in such a manner that the working stroke of the motor part of one of the units both moves its own compressor piston and simultaneously causes the compression stroke of the motor piston and the suction stroke of the compressor of the other unit, means connected to the compression cylinder of one of said units to conduct the compressed air away of said last named cylinder, means in said conducting means operated when the pressure therein exceeds a predetermined amount to connect said conducting means to a space in which the pressure is lower than said predetermined amount, means to supply fuel to the motor cylinder, means controlled by the pressure in said conducting means to reduce the feed of fuel to the motor cylinder of such unit as the pressure in said conducting means decreases, means connected to the compression cylinder of the other unit to conduct away the compressed air, said second conducting means being connected to said first conducting means at a point beyond said pressure operated means, means controlled by the pressure in said second conducting means to control the feed of fuel to the motor cylinder of the second unit, whereby said second unit can function as a motor compressor when the motor piston and the motor cylinder of the first unit therefor act as a compensating cushion.

26. In a motor compressor consisting of at least two motor compressor units each having motor and compressor pistons and motor and compressor cylinders, means connecting said units in such a manner that the working stroke of the motor part of one of the units both moves its own compressor piston and simultaneously causes the compression stroke of the motor piston and the suction stroke of the compressor of the other unit, means connected to the compression cylinder of one of said units to conduct the compressed air away from said last named cylinder, means in said conducting means operated when the pressure therein exceeds a predetermined amount to connect said conducting means to a space in which the pressure is lower than said predetermined amount, means to supply fuel to the motor cylinder, means controlled by the pressure in said conducting means to reduce the feed of fuel to the motor cylinder of such unit as the pressure in said conducting means decreases, means connected to the com-

pression cylinder of the other unit to conduct the compressed air away, said second conducting means being connected to said first conducting means at a point beyond said pressure operated means, means controlled by the pressure in said second conducting means to control the feed of fuel to the motor cylinder of the second unit, whereby said second unit can function as a motor compressor when the motor piston and the motor cylinder of the first unit therefor act as a compensating cushion, said last control means increasing the feed of fuel as the pressure increases up to the pressure at which said first unit idles and then decreasing the feed of fuel as the pressure increases further, causing the second unit to idle when the predetermined maximum pressure is reached.

27. In combination with a motor compressor consisting of at least two motor compressor units each having motor and compressor pistons, motor and compressor cylinders and means connecting said units in such a manner that the working stroke of the motor part of one of the units both moves its own compressor piston and simultaneously causes the compression stroke of the motor piston and the suction stroke of the compressor of the other unit, an engine driven by the air compressed by said motor compressor, means to conduct compressed air from said motor compressor to said engine, means to regulate the speed of said engine including means controlled by the speed of the engine to control the flow of air through said conducting means, said control means reducing the pressure of the air as the speed of the engine decreases, means to supply fuel to the motor compressor, and means controlled by the pressure in said conducting means to reduce the feed of fuel as the pressure in the conducting means decreases.

28. In combination with a motor compressor consisting of at least two motor compressor units each having motor and compressor pistons, motor and compressor cylinders and means connecting said units in such a manner that the working stroke of the motor part of one of the units both moves its own compression piston and simultaneously causes the compression stroke of the motor piston and the suction stroke of the compressor of the other unit, an engine driven by the air compressed by said motor compressor, means to conduct compressed air from said motor compressor to said engine, means to regulate the speed of said engine including means controlled by the speed of the engine to control the flow of air through said conducting means, said control means reducing the pressure of the air as the speed of the engine decreases, means to supply fuel to the motor compressor, and means controlled by the pressure in said conducting means to reduce the feed of fuel as the pressure in the conducting means decreases, said engine comprising a turbine having a plurality of stages, said control means comprising means to direct the air to successively lower stages of the turbine as the speed of the turbine increases.

29. In a motor compressor consisting of at least two motor compressor units each having motor and compressor pistons, means connecting said units in such a manner that the working stroke of the motor part of one of the units both moves its own compressor piston and simultaneously causes the compression stroke of the motor piston and the suction stroke of the

- compressor of the other unit, the diameter and the dead spaces of the compressor cylinders being such that the sum of the motor energy of the one unit and the energy of the compressor cushion of the other unit decreases when the stroke of the pistons reaches their greatest permissible value, while the said sum increases when the stroke of said pistons reaches their smallest permissible value.
- 10 30. A motor compressor of the type described comprising in combination two power cylinders

in line with each other, two pairs of opposed pistons adapted to reciprocate in said cylinders respectively, two pairs of compression cylinders disposed on opposite sides of the first mentioned cylinders respectively and adapted to receive the outer ends of the pistons of said first mentioned cylinders respectively, and rigid linkless means for connecting one piston of one pair to the opposite piston of the other pair.
